REGULATING MEANS FOR TIMEPIECES

Walter Kohlhagen, Waterbury, Conn., assignor
to The Waterbury Clock Company, Waterbury,
Conn., a corporation of Connecticut

Application October 5, 1936, Serial No. 104,013

6 Claims. (Cl. 58—109)

This invention relates to an improvement in timepieces, and particularly to the means for regulating the same.

One of the objects of the present invention is 5 to provide superior means whereby a regulation of timepieces within predetermined limits is facilitated.

Another object is to provide means whereby 10 timepieces which are incapable of being regulated within predetermined limits are detected without undue delay.

A further object is to provide means whereby 15 the accidental displacement of the regulator from a previously-adjusted position will be largely obviated during normal handling of a time movement, as, for instance, in installing such time movement in its case.

A still further object is to provide means whereby 20 the regulator of a timepiece may be stopped at one or more positions intermediate its full scope of movement and still permit such regulator to be moved when desired to any point within its full scope of movement.

With the above and other objects in view, as 25 will appear to those skilled in the art from the present disclosure, this invention includes all features in the said disclosure which are novel over the prior art and which are not claimed by me in a separate application.

30 In the accompanying drawing:

Fig. 1 is a view in rear elevation of a watch movement embodying one form of the present invention and showing the regulator in central position preparatory to a first-test run;

35 Fig. 2 is a broken sectional view taken on the line 2—2 of Fig. 1;

Fig. 3 is a broken rear-elevation of the movement, showing the regulator set preparatory to a second-test run;

40 Fig. 4 is a perspective view of the regulator; and

Fig. 5 is a view in rear elevation of a timepiece illustrating another form which the present invention may assume.

45 The particular timepiece herein chosen for the illustration of the present invention in Figs. 1 to 4 inclusive is in the form of a watch movement having a rear movement-plate 10 which is formed in its edge with an arcuate-notch 11. Radially 50 inward from the said notch 11 the movement-plate 10 is formed with a crescent-shaped opening 12 resulting in the provision of an arcuate-bridge or web 13 which is integral with the said movement-plate.

55 The bridge 13 mounts a bearing 14 constitut-

ing one of the two usual bearings for the staff of a balance-wheel 15 which is provided, in the usual manner of marine-type timepieces, with a hairspring 16 anchored at one end to a stud 17 secured to the movement-plate 10.

Frictionally mounted upon the projecting forward end of the bearing 14 with freedom for turning movement thereon is a regulator generally designated by the numeral 18 and having an outwardly-and-rearwardly-extending arm 19 10 through which the outermost convolution of the hairspring 16 passes in a manner customary in timepiece structures. Directly opposite the arm 19 the regulator 18 is formed with an inwardly-extending flexible arm 20 terminating in a forwardly-bent stop- or detent-finger 21 which is adapted to engage with any one of three detent-recesses A, B, C.

The detent-recess A is located substantially midway between the "S" (slow) end of an arcuate series of graduations 22 imprinted upon the movement-plate 10 and the "F" (fast) end of said series of graduations. The detent-recess B is positioned intermediate the detent-recess A and the "F" end of the graduations 22. Similarly, the detent-recess C is located intermediate the detent-recess A and the "S" end of the graduations 22.

The resiliency of the arm 20 of the regulator 18 causes the detent-finger 21 thereof to release 30 enter a given one of the detent-recesses A, B or C when the arm 20 of the regulator is swung into appropriate position.

For the purpose of a better understanding of the utility of the present invention, let it be presumed that the accuracy-tolerance permitted in timepieces to warrant their being shipped to users is plus or minus two minutes per day (departure from correct time). Under these conditions, the various detent-notches B and C will be spaced 40 from each other a distance which experience has taught will normally provide an adjustment within the accuracy-range referred to.

To illustrate a preferred form of testing and adjusting to which the timepiece embodying the present invention may be subjected, the time-piece-adjuster will first move the regulator 18 so that its detent-finger 21 clicks into the detent-recess A (Fig. 1), after which the timepiece will be given a trial run. If after this first 50 trial run with the regulator in the position A, the timepiece should keep time within the range of plus or minus two minutes per day (which the majority will do), the timepiece may immediately be classed as "suitable for shipment." 55

If, however, after the said first trial run, the timepiece should, for instance, be gaining time at the rate of three minutes per day, the adjustor will move the regulator 18 so that its 5 detent-finger 21 snaps into the detent-recess C, and then subject the timepiece to a second trial run.

If after the second trial run just above referred to with the regulator in the position C, it 10 is found that the timepiece departs no further from correct time than plus or minus two minutes per day (the arbitrarily-selected tolerance), the watch may be immediately classed as suitable for shipment. If, however, after the second trial 15 run with the regulator in the position C, it should be found that the timepiece departs from true time to a greater degree than the predetermined tolerance of plus or minus two minutes per day, then the adjuster may immediately 20 classify the particular timepiece as a "reject."

On the other hand, if upon an initial trial run with the regulator in position A, the timepiece should run at the rate of more than two minutes slow per day, then the adjuster will 25 swing the regulator into the position B and subject the timepiece to a second trial run. If after the second trial run with the regulator in position B, the timepiece should depart from correct time more than two minutes per day, 30 it may be classed as a "reject," otherwise it may be classed as satisfactory for shipment.

Instead of providing a regulator with a detent-finger 21, as in the construction of Figs 1 to 4 inclusive, a regulator 23 such as is shown in 35 Fig. 5 may be employed. This regulator is, like the regulator 18 before described, frictionally mounted upon the bearing 14 and is provided with an outwardly-and-rearwardly-extending arm 24 through which the hairspring 16 passes.

The regulator 23 is also provided with an inwardly-extending arm 25 which is formed with an arcuate-terminal 26 having a series of graduations imprinted upon its face and provided in its curved inner edge with a series of detent 40 notches or recesses 27, 28 and 29 respectively corresponding in function to the detent-recesses A, B and C of the structure of Figs 1 to 3 inclusive. Adapted to successively enter the notches 27, 28 and 29 just referred to is a detent-finger 30 bent from the free end of a detent-spring 31 which is provided with a base 32 in turn rigidly secured to the front movement-plate 10 by any suitable means such as rivets 33-33.

With reference to the structure of Fig. 5, it is 55 sufficient to state that its use will be clear by reference to the foregoing description of the regulating procedure given in connection with the timepiece of Figs. 1 to 4 inclusive, bearing 60 in mind in this connection that the detent-notches 27, 28 and 29 respectively determine the positions of the regulator 23 in the same manner as do the detent-recesses A, B and C before described.

From the foregoing, it will be seen that a large 65 number of timepieces may be passed for shipment with only one trial run after the regulator has been set to its central position A. Such timepieces as do not keep time within the predetermined limits after the first test run are 70 subjected to a second test run with the regulator at either its position B or its position C (dependent upon whether the initial run has indicated that the timepiece is either slow or fast), and 75 if this second test run does not indicate that

the timepiece is keeping time within the permissible range of variation, the same may be immediately classed as a "reject."

Thus, in the mass production of watches, particularly low-priced watches, such timepieces 5 as should properly be rejected may be located rapidly and with relatively unskilled adjusters after requiring not more than two test runs, though it is to be appreciated that the great majority of the watches tested will prove satisfactory after the first test run, and all but a very minor percentage of the remainder will be found satisfactory upon a second test run, but, nevertheless, the very small percentage of timepieces which should be rejected are readily detected and prevented from passing into the 10 hands of users.

As before noted, a timepiece having a deviation of not more than plus or minus two minutes per day may be considered sufficiently accurate 20 to warrant its being shipped from the factory with the expectation that the ultimate user will further refine the setting of the regulator to compensate for the particular conditions under which the timepiece may be used. The factors 25 which affect the fine setting of the watch by a user are conditions of temperature, the length of intervals between winding, vibration, etc.

Owing to the fact that the stop-points B or 28 and C or 29 constitute the limits to which the 30 regulator is set at the factory, the ultimate user has an adjustment-range left to him through which to move the regulator, which range not only includes the central range between the side stop-points B or 28 and C or 29 but also 35 the range intermediate the extreme "F" position and the stop-points B or 28 and between the extreme "S" position and the stop-points C or 29.

In other words, when the timepiece is passed 40 as acceptable for shipment from the factory, the regulator is always in a position short of its extreme "S" or "F" positions.

The invention may be carried out in other specific ways than those herein set forth without departing from the spirit and essential characteristics of the invention, and the present embodiments are, therefore, to be considered in all respects as illustrative and not restrictive, and all changes coming within the meaning and 50 equivalency range of the appended claims are intended to be embraced therein.

I claim:

1. In a timepiece, the combination with the balance-wheel and hairspring thereof; of a regulator for varying the effective length of the said hairspring to thus vary the frequency of oscillation of the said balance-wheel, the said regulator being movable between a predetermined extreme slow position and a predetermined extreme fast position; and releasable stop-means constructed and arranged to releasably stop the said regulator at a point intermediate its extreme slow position and its extreme fast position, the said stop-means comprising a yielding detent and a detent-recess constructed and arranged to releasably receive the same, the said detent-recess being flanked on each of its respective opposite sides by an unrecessed area permitting the relatively-free movement of the said regulator through a 70 considerable range.

2. In a timepiece, the combination with the balance-wheel and hairspring thereof; of a regulator for varying the effective length of the said hairspring to thus vary the frequency of oscillation.

tion of the said balance-wheel, the said regulator being movable between a predetermined extreme slow position and a predetermined extreme fast position; and releasable stop-means constructed 5 and arranged to releasably stop the said regulator at a point intermediate its extreme slow position and substantially the center of its total movement, and also at a point intermediate its extreme fast position and substantially the center 10 of its total movement, the said stop-means comprising a yielding detent and a plurality of detent-recesses constructed and arranged to successively releasably receive the said yielding detent, the said detent-recess being spread apart 15 to provide a space through which the said regulator is relatively free of restraint.

3. In a timepiece, the combination with the balance-wheel and hairspring thereof; of a regulator for varying the effective length of the 20 said hairspring to thus vary the frequency of oscillation of the said balance-wheel, the said regulator being movable between a predetermined extreme slow position and a predetermined extreme fast position, the said regulator being provided with a yielding detent-finger; and a detent-recess formed in a normally-stationary part 25 of the timepiece and located in the path of movement of the detent-finger of the said regulator and at a point intermediate the two extreme positions thereof, the said detent-recess being flanked on each of its respective opposite sides by an unrecessed area permitting the relatively-free movement of the said regulator through a considerable range.

35 4. In a timepiece, the combination with the balance-wheel and hairspring thereof; of a regulator for varying the effective length of the said hairspring to thus vary the frequency of oscillation of the said balance-wheel, the said regulator being movable between a predetermined extreme slow position and a predetermined extreme fast position, the said regulator being provided with a yielding detent-finger; and a plurality of detent-recesses formed in a 40 normally-stationary part of the timepiece in position to successively receive the detent-finger of the said regulator, the said detent-recesses

being spread apart to provide a space through which the said regulator is relatively free of restraint.

5. In a timepiece, the combination with the balance-wheel and hairspring thereof; of a regulator for varying the effective length of the said hairspring to thus vary the frequency of oscillation of the said balance-wheel, the said regulator having a detent-recess and being movable between a predetermined extreme slow position 10 and a predetermined extreme fast position; and releasable stop-means constructed and arranged to releasably stop the said regulator at a point intermediate its extreme slow position and its extreme fast position, the said stop-means including the detent-recess of the said regulator and a yielding detent-finger carried by a stationary part of the timepiece in position to enter the detent-recess in the said regulator, the said detent-recess being flanked on each of its respective opposite sides by an unrecessed area permitting the relatively-free movement of the said regulator through a considerable range.

6. In a timepiece, the combination with the balance-wheel and hairspring thereof; of a regulator for varying the effective length of the said hairspring to thus vary the frequency of oscillation of the said balance-wheel, the said regulator being movable between a predetermined extreme slow position and a predetermined extreme fast position; and releasable stop-means constructed and arranged to releasably stop the said regulator at a point intermediate its extreme slow position and substantially the center of its total movement, and also at a point 35 intermediate its extreme fast position and substantially the center of its total movement, the said stop-means including a plurality of detent-recesses formed in the said regulator and a yielding detent-finger carried by the normally-stationary part of the timepiece and adapted to successively engage with the detent-recesses of the said regulator, the said detent-recess being spread apart to provide a space through which the said regulator is relatively free of restraint. 45

WALTER KOHLHAGEN.
